UNITED STATES PATENT OFFICE.

JOHN F. O'ROURKE, OF NEW YORK, N. Y.

METHOD OF MAKING EXCAVATIONS.

1,179,750.

Specification of Letters Patent. Patented Apr. 18, 1916.

Application filed December 15, 1915. Serial No. 66,889.

To all whom it may concern:

Be it known that I, JOHN F. O'ROURKE, a citizen of the United States, and resident of New York city, borough of Manhattan, in the county of New York and State of New York, have invented certain new and useful Improvements in Methods of Making Excavations, of which the following is a specification.

10 In making excavations in the ground for subways, trenches, cellars and foundations for buildings, and the like, it has been the general practice to drive sheet piling into the ground surrounding the excavation to a 15 suitable depth to hold back surrounding earth, and as the earth between such sheet piling was excavated to apply against the piling timbers, called rangers, properly spaced apart and braced by intervening beams or braces; then to drive such sheet piling farther down, again excavate the 20 earth between the piling, then apply more rangers and braces to the piling, and so on. After the excavation has been made to about 25 the depth equal to the length of the sheet piling driven down as aforesaid, if it be intended to carry the excavation down farther more sheet piling is again driven, but within the rangers of the first level of sheet piling, and excavation between such piling and 30 bracing thereof is continued as before described, and so on in as many levels or stages downwardly as are required, and in accordance with the depth of the excavation and 35 the length of the several stages of sheet piling which varies according to circumstances and the different kind of earths. By such operations the width of the proposed excavation is fixed by the width between the lowermost stage or level of sheet piling, but 40 more earth has to be excavated above the lowermost stage of operations than required for producing the width at the bottom of the proposed excavation, because of the requirement to drive the subsequent stages of 45 sheet piling within those previously driven, whereby the upper portions of the excavation are necessarily much broader than the final excavation requires. By the use of 50 such vertically disposed sheet piling it is not practical to inspect the earth behind the piling, or to fill in where earth may have fallen in, as the work proceeds downwardly, or to fill spaces outside the sheet piling to 55 hold back surrounding ground, except from the top, and the danger, noise and cost in-

volved in driving sheet piling is so great as often to create a dangerous nuisance. It is not unusual, also, for the sheet piling to kick out at the bottom of the drive, leaving the 60 inclosed excavation too small so that the excavation may have to be refilled, the sheeting pulled out, and the work begun over again.

The object of my invention is to facilitate and render more safe and economical the construction of excavations in the ground intended for subways, cellars, foundations and analogous purposes, and to enable such excavations to be made from top to bottom 70 at substantially the width of the proposed or required excavation, thereby also enabling inspection of the surrounding ground and the filling in behind the sheeting to restore ground that may be lost in the placing 75 of the sheeting, or through subsequent runs of the ground behind the same, as required as the work proceeds.

In carrying out a feature of my invention, I dig spaced relatively narrow trenches to 80 a suitable depth, the outside walls of which trenches are to form the outside walls of the work, and brace or shore from side to side the walls of said trenches as the digging proceeds, leaving unexcavated ground temporarily between the trenches. The walls of the trenches may be sheeted with planks laid horizontally, the planks being preferably suitably spaced apart to permit of tamping solidly behind them, through the 85 spaces between the planks, suitable material to hold back the ground, temporary braces in each trench being placed between opposing planks or between vertical timbers spanning several planks. After such 90 opposed trenches have been dug to a desired depth and braced inside themselves, as stated, vertically disposed timbers are placed against the outer walls of the trenches between the previous bracing of same, and said 95 timbers are in turn braced and wedged against the inner walls of the trenches so that the first placed bracing of the trenches may be removed in whole or in part as may be desired. When the trenches on opposite sides have been thus fitted with vertical 100 rangers or timbers (corresponding to the horizontal rangers commonly used when vertically disposed sheet piling is employed) that is to say, when the timbers crossing the 110 planking are in place, the excavation is made secure by the braces against the vertical

timbers being held securely by the inner walls of the trenches, which are held in turn by the unexcavated material between the opposite trenches. The next operation is the removal of the material between the trenches. For this purpose I place transversely disposed timbers, of sufficient length and strength, between the vertical rangers on opposite or outer sides of the excavation 10 as the latter is carried downward, the weight of the material on the outside being taken up on such cross timbers by means of wedges or screw jacks, as desired, which thus relieve the pressure on the cross braces in the trenches, and the latter can be taken out 15 as fast as the excavation proceeds without allowing an inward movement of the outer walls of the excavation. As it would not be always practicable to excavate the middle 20 ground down to the bottom of the trenches before putting in the permanent cross brace at that level, it is expected that temporary cross braces will be used from time to time to hold the vertical timbers until the permanent ones lower down are placed and wedged. While the middle excavation can 25 be done in the above manner to the bottom of the trenches, it would also be practicable, as well as desirable, in the case of deeper excavations, to continue sinking the side 30 trenches, simultaneously with the middle excavation and keeping the side trenches ahead of the middle excavation, with additional vertical rangers also placed in advance so 35 that they might be joined to those above in convenient lengths and the horizontal permanent braces placed to catch the bottom of one timber and the top of another. Or, if 40 desired, a timber bolster can be placed at the joint between rangers to distribute more securely the thrust of the cross timber on the ranger above and below.

In the manner described an excavation in earth can be safely carried down in dry 45 ground to any desired depth with a maximum of safety and a minimum of cost, and which also permits of keeping the sides of the excavation in corresponding vertical planes from top to bottom.

50 Where the excavation is to have different levels, both trenches and the intermediate ground may be carried down to the depth of one proposed level of the excavation, and then from the bottom of such level one of 55 such trenches may be carried down to the lower desired level, together with another trench spaced therefrom, with the outer walls of said trenches spaced approximately the width of a lower level of the excavation, 60 both trenches being continued down and the intermediate ground excavated to such lower level, the shoring and braces being carried out, in the manner before described.

It will be understood that as the excavation 65 proceeds downwardly, any supports,

braces and the like may be spaced apart and built within the excavation from above downwardly for the convenience of the final work in any wellknown or desired manner, and that after the excavation has been completed, subways, structures, foundations, cellars and the like may be erected therein, and, where required, the earth filled back thereover in the excavation in any well-known manner.

75 For some classes of work the outer wall of the excavation can be permanently braced while the work is progressing otherwise than by the aforesaid horizontal braces, as hereininafter explained.

80 My invention further comprises novel details of improvement that will be more fully hereininafter set forth and then pointed out in the claims.

85 Reference is to be had to the accompanying drawings forming part hereof, wherein,

Figure 1 is a cross sectional view illustrating steps in carrying out my improvement; Fig. 2 is a detail hereininafter referred to; Fig. 3 is a plan view; Fig. 4 is a fragmentary perspective view of a portion of the excavation. Fig. 5 is a cross section of an excavation substantially completed in accordance with my improvements; Fig. 6 is an enlarged cross section substantially on the line 95 6, 6, in Fig. 3; Fig. 7 is a plan view illustrating my improvements utilized in digging a cellar; Fig. 8 is a sectional view thereof, showing early stages of the work, and Fig. 9 is a similar view showing further stages 100 of the work.

In accordance with my improvements, at the place where an excavation in the ground is to be made, I dig two trenches 1, 2 of suitable width and narrower than the proposed excavation, to a suitable depth, and spaced apart in such a manner that the outer walls 3, 4, of such trenches may be spaced approximately the distance of the width of the proposed excavation, leaving between the 110

trenches temporarily unexcavated ground at 5. As said trenches are dug, their walls or sides are braced or shored, preferably with longitudinally extending planks or cribbing 6, 7, the planks or cribbing 6 being 115 shown applied along the outer walls or sides 3, 4, of the trenches, and the planks or cribbing 7 applied along the inner walls or sides 3^a, 4^a of the corresponding trench, temporary braces 8 being placed between opposed planks 6, 7, in the respective trenches.

Such temporary braces 8 are preferably placed against vertically disposed boards or the like 9 that are laid against the planks or shoring 6, 7. After the trenches have 120 proceeded to a suitable depth, vertically disposed rangers or timbers 10 are placed against the outer walls of the trenches, in position between the previous bracing 8, 9, of the trench walls, and said rangers or 125

- timbers 10 are themselves braced and wedged against the inner walls of the corresponding trenches, by means of suitable braces 8^a extending between the rangers or timbers 10 and vertically disposed boards or the like 9^a that are placed against the planks 7 (Figs. 2 and 3), whereby the first named bracing 8, 9, may be removed in whole or in part as may be desired. The vertical rangers or timbers 10 will thereupon temporarily remain braced against the inner walls 3^a, 4^a of the trenches, the planks 7 then remaining in place by reason of the unexcavated material between the trenches.
- 15 After the upper rangers or timbers 10 have been placed as stated a suitable amount of the intermediate ground 5 is first excavated to admit cross braces or timbers 11 of sufficient length and strength to be inserted between the upper parts of opposing rangers or timbers 10, and the work of continuing the excavation at 5 proceeds until space for another cross timber 11 is made. When such brace is placed and wedged the side 20 trenches are continued with the same operations of bracing, etc., corresponding planks 7 being removed as the excavation at 5 proceeds. When the trenches have been dug downwardly sufficiently to admit additional vertical rangers or timbers 10 the latter are placed beneath, or they may be joined to, the first set of rangers or timbers 10 above, in convenient lengths, and against the outer walls 3, 4, and the horizontal braces or 25 beams 11 may be placed to oppose the bottom of one ranger or timber 10 and the top of another, or if desired a timber bolster A may be placed at the joint between said rangers or timbers 10 to distribute more 30 securely the thrust of the cross braces 11 on the rangers or timbers 10 above and below, as indicated in Fig. 5. The lower portions of the rangers or timbers 10 set in place as last referred to, may be temporarily braced 35 against the inner walls 3^a, 4^a by the braces 8^a, 9^a as before described, the excavation 5 being continued a suitable depth, and, where desired, temporary braces 11^a and wedges or screw jacks 13 may be inserted between opposing rangers or timbers 10, until the excavation has proceeded downwardly sufficiently to admit the more permanent braces 11 between opposing rangers or timbers 10, as illustrated in Fig. 1. It thus will be 45 understood that as the work proceeds, the opposing walls of the trenches are not only first and temporarily braced by the bracing means 8, 9, but are secondarily braced by the bracing 10, 8^a, 9^a, and then by the more permanent bracing 10, 11, whereby the weight of the material on the outside of the excavation above the trenches is taken up by the cross timbers 11, which may remain permanently in position while the work is being 50 carried on. Wedges indicated at 12 may be driven between the parts 10, 11 to make firm bracing thereof. It will be observed that the outer planks 6, opposing the timbers 10, remain in place as the work proceeds, although the planks 7 are removed successively. The work may proceed stage by stage until the trenches have reached the desired low level, and the completed excavation of the desired width and to the desired depth has been accomplished, as, for instance, to the level indicated at 14 in Fig. 1. In the trenches partitions between the planks or shoring 6, 7, may be installed as indicated at 15, Figs. 4 and 6.
- During the progress of the work, and after the intermediate ground at 5 has been excavated, any suitable structural work, such as cross and longitudinal braces, beams and the like, indicated generally at 16, may be erected in the excavation, the work proceeding from above downwardly, as indicated in Figs. 4 and 5, whereby overhead installations may be made, such as roadways for the support of rails, roadbed, and the like indicated at 17, 18 (Fig. 5), to enable the work of excavation to be carried out beneath a roadbed without undue interfering with traffic thereon.
- If it be desired to construct the bed or bottom of the excavation on more than one level, as indicated in dotted lines in Figs. 1 and 5, the excavation may be carried down to its full width to one of such levels, as at 14, and one of the trenches used for such purpose, as indicated at the lefthand side in Fig. 1, may be continued down to the low level as at 14^a. The other trench may be started at the level 14 and at a desired distance from the first named trench (as indicated by the dotted lines at the right in Fig. 1), and continued downwardly with the latter trench, or spaced trenches otherwise located may be continued down, the walls or sides of the trenches being braced, and intermediate ground at 5^a excavated as such trenches proceed downwardly, in manner before explained, the vertical rangers or timbers 10 and the transverse braces 11 being installed between the side walls of the narrower portion of the excavation, to the lower level 14^a, as stated and as illustrated in Fig. 5.
- By preference, the planks or shoring 6 will be so set as to present spaces therebetween, indicated at a, which may be accomplished by placing blocks b upon the edges of adjacent planks so that the latter will be spaced apart, whereby the ground may be inspected through the spaces a, and earth may be filled in behind the planks in spaces where the earth may fall away, although any other suitable or desired sheeting or shoring may be used. It will be understood that as the trenches proceed downwardly, the planks 6, 7, will be placed in 125

position from beneath those previously set, and that the braces 8 in conjunction with the vertical boards 9, retain such planks temporarily in position until the permanent 5 vertical rangers or timbers 10 have been placed in position and braced by the transverse beams 11.

By means of my improvements above described, it will be understood that the extreme width of the proposed excavation can be determined by the distance between the outer walls or sides 3, 4, of the spaced trenches 1, 2, and that such walls or sides may be dug straight down, the advancing of 10 the trenches ahead of the digging of the intermediate ground 5 permitting secure bracing or shoring of the walls of the trenches and excavation in a continuous manner, enabling most secure bracing together 15 of the outer walls 3, 4 of the excavation to be effected, stage by stage or step by step, and that the outer walls of the trenches are securely temporarily braced against the intermediate ground 5, and permanently 20 braced by the vertical beams 10 and transverse beams 11 before the main portion at 5 or 5^a is excavated. Also, that as the latter portion of the excavation is removed, it will have no injurious effect against the outer 25 walls of the excavation because of the complete bracing of the latter before removal of the intermediate ground. By this means I am enabled to make an excavation having approximately the same width at all points, 30 where such is required, without being obliged to remove ground wider at some stages than is desired for the width of the completed or proposed excavation. Hence, a saving is effected not only in the amount 35 of material removed, but also in the amount of material required to be replaced where the excavation is to be refilled over some subterranean structure, such as where subway structures are built for railway tracks 40 beneath roadways and under buildings, where the earth is to be refilled over the roof of the subway after the latter has been erected in the excavation.

Instead of bracing the outer walls together, such outer walls may be otherwise braced, as for instance as illustrated in Figs. 50 7, 8 and 9. In the last named figures the excavation may be considered to be for a cellar and a trench 1 may be dug at one or more of the proposed walls of the cellar and shored by the planks 6, 7, which may be temporarily braced together by the braces 8 in the manner before described. When the trench is thus dug, shored and braced the 55 vertical rangers 10 may be placed in position and braced against the wall 3^a by the braces 8^a bearing against the uprights 9^a laid against the planks or shoring 7, as in Fig. 8. A suitable amount of the ground 60 at 5^b may then be dug, say in an inclined

manner, or an inclined ditch may be dug, whereby braces or timbers 11 may be set at an inclination, their upper ends being applied against the upper portion of the corresponding vertical rangers 10, and held 70 against the same as by cleats 20, nailed or otherwise secured to the rangers 10, the lower ends of said braces 11 being placed against suitable abutments 21 laid at the bottom of the excavation, a corresponding 75 portion of the upper planks 11 being removed as the work progresses. After such upper set of braces 11 have been placed in position, and ground at 5^b suitably excavated, another set of braces 11 may be applied to the rangers 10, as at a stage below the first named braces 11, the second named braces 11 being held by corresponding cleats 20 and placed against abutments 22 at the bottom of the excavation, as illustrated in 80 Fig. 9. The same operations may be carried out for any suitable depth to which the excavation is to be carried, braces 11 being applied as required at lower stages as the work of excavation proceeds. In this manner 85 excavations for cellars, foundations and the like may be conveniently made and the outer walls shored and braced, this feature of my invention being particularly applicable where the excavation is of a width not to 90 conveniently permit insertion of transverse braces 11 between opposing walls of the excavation as illustrated in Fig. 1, or in cases where the character of shoring and bracing illustrated in Figs. 7, 8 and 9 may 95 be found preferable or more desirable.

In the manner described the expensive, troublesome, and often dangerous method of driving vertical sheet piling is avoided.

Having now described my invention what 100 I claim is—

1. The method of producing an excavation consisting in making a trench, lining opposing walls thereof with sheeting, bracing opposing sheeting together in the trench, 110 bracing the proposed outer wall of the excavation independently of the inner wall of the trench, and excavating the ground adjacent to the inner wall of the trench leaving the outer wall as a wall of the excavation. 115

2. The method of producing an excavation consisting in making a trench, lining opposing walls thereof with sheeting, bracing opposing sheeting together in the trench, placing vertical rangers against the sheeting along the proposed outer wall of the excavation, temporarily bracing said rangers against the opposite wall of the trench, and substituting other braces from without the trench against the vertical rangers as the 120 general excavation proceeds. 125

3. The method of producing an excavation consisting in making spaced trenches, bracing the walls of said trenches, excavating ground between trenches to produce the 130

desired width of excavation, and bracing the walls of said excavation.

4. The method of producing an excavation consisting in making spaced trenches, bracing the outer walls of such trenches against the inner walls thereof, excavating material between said trenches for the desired excavation, and bracing the outer walls of said excavation together.

10 5. The method of producing an excavation consisting in making spaced trenches, placing shoring along the walls of said trenches, bracing the shoring in each trench by placing braces between such shoring to hold back the ground at the sides of and between the trenches, excavating ground between the trenches above the bottom of the latter, and bracing the outer shoring of said trenches above and within the trenches by 20 inserting beams between said shoring.

6. The method of producing an excavation consisting in first making spaced trenches to a suitable depth, shoring the inner and outer walls of said trenches, removing ground between said trenches together with the corresponding shoring at inner walls of the trenches opposing such removed ground, and bracing against each other the shoring of the outer walls of the trenches after such ground between the trenches has been removed.

7. The method of producing an excavation consisting in making spaced trenches,

placing shoring along the walls of said trenches, bracing together the opposing shoring of each trench, placing upwardly disposed rangers against the shoring at the outer walls formed by the trenches extending into the trenches below the level of the ground between the trenches, and removing 35 intermediate ground and the shoring at the inner walls of the trenches above the lower ends of said rangers.

8. The method of producing an excavation consisting in making spaced trenches, placing shoring along the walls of said trenches, bracing together the opposing shoring of each trench, placing upwardly disposed rangers against the shoring at the outer walls formed by the trenches, bracing 40 opposing rangers together above the ground intermediate the trenches, bracing the lower portions of said rangers against such intermediate ground within the trenches below the level of such intermediate ground, and 45 removing intermediate ground, braces in the trenches, and shoring at the inner walls of the trenches above the lower ends of said rangers.

Signed at New York city, in the county 50 of New York, and State of New York, this 13th day of December, A. D. 1915.

JOHN F. O'ROURKE.
